UNITED STATES PATENT OFFICE.

LOUIS JACOBS AND LOUIS A. BAIER, OF SEATTLE, WASHINGTON.

SHIFT-KEY ATTACHMENT FOR TYPE-WRITING MACHINES.

1,184,532.

Specification of Letters Patent. Patented May 23, 1916.

Application filed August 9, 1915. Serial No. 44,573.

To all whom it may concern:

Be it known that we, LOUIS JACOBS and LOUIS A. BAIER, citizens of the United States, residing at Seattle, in the county of King and State of Washington, have invented certain new and useful Improvements in Shift-Key Attachments for Type-Writing Machines; and we do hereby declare the following to be a full, clear, and exact description of the invention, such as will enable others skilled in the art to which it appertains to make and use the same.

The present invention relates to improvements in shift key attachments for type-writing machines, and consists in the constructions, combinations and arrangements herein described and claimed.

In the accompanying drawings forming a part of this application, and in which similar reference symbols indicate corresponding parts in the several views: Figure 1 is a side elevational view of the improved attachment shown connected to the key lever of a typewriter illustrated in dotted lines. Fig. 2 is an enlarged horizontal sectional view through the casing. Fig. 3 is a transverse sectional view on the line 3-3 in Fig. 2. Fig. 4 is a fragmentary perspective view of the connecting rods and clamping device; and Fig. 5 is a fragmentary perspective view of the typewriter key lever and upper connecting rod.

Referring more particularly to the drawings, 1 designates the key lever of a typewriter, indicated in dotted lines in Fig. 1, and supported on a table 2 in which is provided an opening 3 for the passage of the upper connecting rod.

The key lever 1, as more particularly seen in Fig. 5, is perforated at 4 to receive a projection 5 formed by bending the upper end of a connecting rod 6 at substantially right angles to the latter. On the connecting rod 6 is secured, in any suitable manner, a sleeve 7, on the upper end of which is formed a yieldable bow spring 8 having its outer free end arranged to normally rest against the outer end of the projection 5, as clearly disclosed in Fig. 5, and whereby said rod 6 is maintained in connection with the key lever 1.

The rod 6 is slidably connected to a similar rod 9, and a two-part clamp device, illustrated in Fig. 4 as being comprised of a pair of sections 10 and 11 formed with complementary semi-cylindrical grooves, engages the

rods 6 and 9, said sections 10 and 11 being held in tight frictional engagement by a screw or other device 12. The ends of the rods 6 and 9, where held by clamps 10 and 11, are threaded. The semi-cylindrical grooves in 10 and 11 are similarly tapped to insure firm grip on rods. The inner ends of the rods 6 and 9 are bent angularly, as indicated at 13 and 14 respectively, and are bent 65 into eyes 15 and 16 for slidably engaging the respective rods.

The lower end of the rod 9 is provided with a flange 17 which may be advantageously formed of a pair of lock nuts, and 70 said flange 17 is adapted to be engaged by the projecting end of a lever 18 formed with a slot 19, as shown in Fig. 2, closed by a yieldable spring 20. The rod 9 may be readily detached by prying open the spring 75 20, and may be inserted in a similar manner.

The lever 18 operates in a slot 21 formed in the rear wall of a casing 22, and is fulcrumed between a pair of brackets 23 mounted on the base 24 of said casing. The casing 22 is flanged, as indicated at 25, and secured to the base 24 and to the floor or other supporting surface by screws or other means 26. The lever 18 is constructed with a projecting rear end between which and the base 24 is arranged a coil spring 27 for normally maintaining the outer end of the lever in the elevated position shown in Figs. 1 and 3. The lever 18 is further notched for receiving a similar lever 28 fulcrumed in 90 brackets 29 supported on the base 24 of the casing, and arranged with its outer end operating in a slot 30 in the casing 22, whereby said lever 28 is guided. Fitted in a similar notch in the lever 28 is the shank 31 of a 95 foot pedal 32, and the shank is pivoted in brackets 33, also mounted on the base 24 within the casing, and the same operates in a slot 34 in the front wall of the casing 22. Adjacent the foot pedal 32 is a flanged lug 100 35 arranged to provide a support for the foot when not operating the pedal. This serves to keep any weight of the foot from resting on the pedal which would tend to disturb the shift key.

In operation, the foot pedal 32 is depressed, and through its engagement similarly depresses the lever 28 about its fulcrum 29. In a similar manner the lever 28 oscillates the lever 18 in opposition to the 110 influence of the coil spring 27, and the lever 18 draws upon the rods 9 and 6, thus de-

pressing the key lever 1. When the foot pedal 32 is released, the spring 27 will restore the lever 18 to initial position, and, due to the several connections, the lever 28 5 and foot pedal 32 will be similarly restored and the shift key lever 1 will be returned by action of its usual mechanism. The clamp device 10 and 11 permits of adjustment between rods 6 and 9 to vary their combined 10 length to suit the distance between the typewriter table or desk and the floor.

The connection illustrated in Fig. 5 permits of the device being readily attached and detached from the typewriter, and for 15 transportation or closing of desk the lower end of the rod 9 may be readily disengaged from the lever 18 by prying open the spring 20.

We are aware that devices for accomplishing a similar purpose have been heretofore proposed, and we do not claim the same broadly. It is to be understood, however, that changes may be made in the herein described device without departing from the 25 spirit of the invention, provided such changes fall within the scope of the appended claims.

We claim:

1. The combination with a typewriter, of 30 a shift key actuating mechanism therefor comprising a casing, a treadle pivotally mounted in said casing and projecting for operative engagement, a lever fulcrumed in said casing at right angles beneath the 35 treadle and adapted to be oscillated when the treadle is depressed, a second lever pivoted in said casing at right angles beneath said first-named lever and in connection to be oscillated thereby when the treadle 40 is depressed, spring means connected between said casing and last-named lever for restoring the parts to initial position after each actuation, and a connection between said last-named lever and the typewriter 45 shift key, substantially as described.

2. The combination with a typewriter, of 50 a shift key operating mechanism therefor comprising an angle casing arranged to be

located beneath said typewriter, a treadle mounted within said casing and projected 55 for engagement by the operator's foot, a rest on the adjacent arm of the casing to receive the side of the operator's foot when the treadle is not to be depressed, and connections between said treadle and the typewriter shift key, substantially as described.

3. The combination with a typewriter, of 60 a shift key actuating mechanism therefor comprising an angle casing located beneath the typewriter, a treadle pivotally mounted in said casing and projecting for engagement by the operator's foot, a rest on said casing adjacent the treadle for receiving the side of the operator's foot when not engaged in depressing said treadle, a lever 65 fulcrumed in one arm of said casing angularly beneath said treadle for engagement and operation therefrom, a second lever fulcrumed in the other arm of said angle casing and at an angle beneath said first-named 70 lever to be oscillated thereby, means for restoring the parts to initial position after each actuation, and a connection between said last-named lever and the typewriter shift key, substantially as described.

4. The combination with a typewriter, of 75 a shift key operating mechanism therefor including foot-operated means, and an adjustable connection between said foot-operated means and the typewriter shift key in 80 cluding a pair of relatively movable rods having their ends arranged overlapped and parallel, said parallel ends being threaded, the terminals of said rods being bent and rolled to provide eyes engaging the companion rods for slidably connecting the same, and clamp means for securing said rods in adjusted position and provided with tapped grooves for receiving the threaded portions of said rods, substantially as de- 85 90 scribed.

In testimony whereof, we affix our signatures.

LOUIS JACOBS.
LOUIS A. BAIER.
